[57] CLAIM

The ornamental design for a bottle, as shown and described.

DESCRIPTION

FIG. 1 is a front view of a bottle showing my design; FIG. 2 is a back view thereof;

FIG. 3 is a left side view thereof;

FIG. 4 is a right side view thereof;

FIG. 5 is a top view thereof; and,

FIG. 6 is a bottom view thereof.

The characteristic feature of the design resides in the floral surface ornamentation.

FIG. 3

FIG. 2

FIG. 1

FIG. 6

FIG. 5

FIG. 4
